UNITED STATES PATENT OFFICE.

HENRY C. PRESTON AND OTHNIEL PRESTON, OF HORNELL, NEW YORK.

BEATER FOR EGGS, CREAM, CUSTARDS, &c.

933,580.

Specification of Letters Patent. Patented Sept. 7, 1909.

Application filed March 27, 1909. Serial No. 486,118.

To all whom it may concern:

Be it known that we, HENRY C. PRESTON and OTHNIEL PRESTON, citizens of the United States, residing at Hornell, in the county of Steuben and State of New York, have invented certain new and useful Improvements in Beaters for Eggs, Cream, Custards, &c., of which the following is a specification.

10 This invention relates to beaters for eggs, custards, etc., and more particularly to the such devices of this class operated by hand.

One object of the present invention is to provide a beater which is simple and cheap 15 in construction, and effective in operation.

Another object is to provide a device 20 which can be operated by one hand, so as to allow the receptacle containing the material to be beaten to be held by the other hand, or material introduced or added by such free hand.

With these, and other objects which will appear in the general description, the invention comprises a device of the character 25 described, having a handle into and out of which a shank, having a spiral groove thereon, is adapted to be worked; also means on the handle engaging the groove to cause a rotary motion of the shank, and a beater 30 member at the outer end of said shank.

In the accompanying drawings, in which like reference characters designate like parts,—Figure 1 is a perspective view of the invention; Fig. 2 is a longitudinal section 35 through the handle; Fig. 3 is an enlarged perspective view of the ferrule of the handle; Fig. 4 is a detail view of the shank; Fig. 5 is a perspective view of a modified form of our invention; Fig. 6 is a longitudinal section through the handle; Fig. 7 is an enlarged perspective view of the ferrule; Fig. 8 is a detail view of the shank.

In the drawings, 1 represents the handle, which is provided with a longitudinal bore 45 2 for the reception of the spiral spring 4. The handle is provided with a reduced portion at one end to receive a ferrule 3. The ferrule 3 has a serrated aperture 9, the projections 10 formed by said serrations and 50 numbered four projected inwardly.

Referring more particularly to Fig. 1, a shank 5 having a cylindrical enlargement or head 7 lies within the bore 2, and fits more or less snugly. Encircling the shank 5 and 55 arranged within the bore of the handle and

bearing against the shoulder 8 and inner face of the ferrule 3, adjacent to the aperture 9, is a smaller spiral spring 11. The shank 5 is provided with a spiral groove 6 extending to within a suitable distance of the outer 60 end, where said shank has thereon bowed beater members 12. The projections 10 on the ferrule 3, lie in the groove 6.

In Fig. 1 the shank 5 is shown as composed of two pieces of wire bent on themselves, and having their ends twisted to form a spiral. The looped ends 13 and 14 are bowed, and cross each other at right angles at 15. The loops or bowed members are crimped as at 16. These form the beater 70 members, or dashers.

Referring to the modification shown in Figs. 5 to 8, it will be seen that the shank is formed of a single bar 5' having a spiral groove 6', cut nearly its entire length. The 75 projections 10' in this case are two in number. The beater or dasher members 12' are crimped strips of metal 13' and 14', suitably secured to the shank 5', and arranged at right angles to each other and secured 80 together at 15'.

The operation is as follows: The handle 1 is grasped in one hand, and the point 15 made to rest on the bottom of a receptacle. Pressure is then exerted on the handle. The 85 shank 5 will recede into the handle, against the spring 4, and compressing said spring within the bore 2. The projections 10, engaging in the groove 6, will cause the shank to rotate, and the beaters with it. Upon releasing pressure on the handle, the same will rise by means of the expansion of the spring 4. The spring 11 serves to release the jar 90 incident to the upward limit in the movement of the handle. The downward pressure and upward releasing of the handle cause the shank to rapidly rotate, first in 95 one direction, and then in the other.

It will readily be seen that a device has been provided which is simple in operation, 100 and provides for the use of the other or free hand to hold or fill the receptacle.

What we do claim as our invention, and desire to secure by Letters Patent, is:

1. A beater, having a handle, a spring 105 pressed and rotatable shank operating within said handle, a head on said shank forming a shoulder at its intersection with said shank, a ferrule having means for rotating said shank, and a cushioning means within said 110

bore of the handle and arranged between said shoulder and said ferrule, substantially as specified.

2. A beater having a handle, a rotatable spring pressed shank operating within said handle, means on the handle for rotating said shank, a shoulder enlargement on one end of the shank, and beater members on the other end of the shank, a ferrule on said handle, and a spring embracing said shank and bearing on said shoulder enlargement

and said ferrule, and said spring being arranged within the bore of the handle, substantially as specified.

In testimony whereof we affix our signatures in presence of two witnesses.

HENRY C. PRESTON.
OTHNIEL PRESTON.
